PHOTOELECTRIC PAPER CUTTING
CONTROLFinn H. Gulliksen, Wilkinsburg, Pa., assignor to
Westinghouse Electric & Manufacturing Com-
pany, a corporation of Pennsylvania

Application February 1, 1932, Serial No. 590,267

1 Claim. (Cl. 164—68)

This invention relates to electrical control systems for apparatus operating on material.

More specifically, this invention relates to electrical control systems, involving thermionic means 5 and light sensitive means, for controlling the relative positions and relative speeds of certain parts of a machine operating on a web.

In the art of paper cutting or printing, the 10 operation on the paper or web of material, when moving from a supply reel past certain rolls to the cutter, nearly always involves slippage, thus the paper becomes shifted relative to the cutter or other machine. Even when there be no slippage, the hygroscopic characteristics of paper, or 15 temperature or both, cause a change in its dimension with changes of relative humidity and/or changes in temperature with the result that the cutter will not cut the paper along the desired line. Slippage and the moisture effect may, of course, occur simultaneously and tend to compensate or to cumulate.

It is an object of this invention to control the 20 operation of apparatus operating on a web so that the required operation on the web will take place at the right point regardless of the slippage of the web or the change of dimension of the web or both.

Another object of this invention is to control the 25 relative speeds of a cutter and the feeding means of a machine operating on a web by photo-electric control means.

A further object of this invention is to control the 30 position of the web in a machine operating on a web by photo-electric control means.

Another object of this invention is to control the 35 relative speeds of certain parts of a machine operating on a web and the relative position of these parts by the cooperative action of photo-electric and thermionic means.

Other objects and advantages will become apparent 40 from a study of the following specification when considered in conjunction with the accompanying drawings, in which:

Figure 1 is a diagrammatic showing of the cutter, web-feeding device and driving means therefor; and

Fig. 2 is a diagrammatic showing of part of the 45 control system for controlling the operation of some of the equipment shown in Fig. 1.

Referring more particularly to Fig. 1 of the 50 drawings, 126 designates an induction motor, or any other electric motor, supplied with electrical energy from the buses 201, 202 and 203 through the line contactor 129. A cutter 29 is coupled to 55 the motor 126 through the reduction gear 131.

The motor 126 is also utilized to drive the web feeding mechanism or roll 28, the operation of the web feeding mechanism taking place through a mechanical differential, or localizer, and a speed changer both of which may be adjusted by a pair 5 of motors 107 and 103, respectively. The web feeding mechanism 28 is coupled to a shaft 133 through suitable reduction gearing.

Associated with the apparatus for operating on the web is a light sensitive device 17 and a 10 source of light 27 mounted in the housing 221 provided with the slit 228.

Some of the control equipment appears on Fig. 1 but the main part of the control equipment is shown in Fig. 2 and consists of a plurality of 15 amplifier tubes 18, 19 and 24 and a pair of hot cathode tubes 22 and 23.

The theory of operation of the scheme, generally stated, embodies the synchronizing of a spot I, printed on the paper, with the operation 20 of some contact members 30, 31 and 32 designed to rotate with the cutter when the cut is right on the spot or at some predetermined distance from the spot. When the spot is synchronized the brushes on the contact members do not engage 25 the contact segments thereof when the photo-cell impulse from the cell 17 is obtained. If however, the spot I is not in proper position with reference to the cutter 29, the impulse given to the photo-cell 17 by the increase of current flowing 30 therein modifies the operation of amplifier tube 19 and this modified operation, because of the fact that the contact segments coupled to the cutter are not in synchronism with the spot on the paper or web, causes the hot cathode tube 35 23 or 22, as the case may be, to break down thereby operating either relay 1 or relay 2. When one of these relays has operated, one of the contactors 34 or 35 may be operated to establish a circuit 40 for the motors 107 and 103 (see Fig. 1).

Operation of the motor 107 causes a shift in 45 position between the cutter 29 and the web feeding roll 28, whereas the operation of motor 103 causes a change in the speed difference between the cutter and the web feeding roll 28. Since, 50 as here broadly indicated, both motors 107 and 103 are caused to operate, the change in speed relation between the cutter and the web feeding mechanism is in the direction to make the correction necessary to perfectly synchronize this spot 55 on the web and the knife of the cutter. The operation of the motor 107, operating on the housing 122 of the differential mechanism, causes a shift in position between the cutter and the web feeding roll 28 in such a direction as to cor- 55

rect for the amount of asynchronous operation between the cutter blade and the spot on the web. After the motor 107 or 103 has operated for a short interval of time determined by a timing circuit arrangement described more in detail hereinafter, the correction necessary may have been completed and no further synchronizing operation is necessary.

An important factor in any cutter control application is the mechanical arrangement of the feed-roll, speed-changing device, and the localizer equipment. In some cutting applications, the slip of the paper is relatively small or substantially zero or practically constant so that when the speed ratio between cutter and the feed roll is once adjusted, the entire control can be obtained by means of the localizer adjustment, namely, the positioning of the housing 122 of the differential mechanism.

In other applications, the slip varies considerably from time to time due to changing air moisture and air temperature and a speed ratio change as well as a localizing change is required in order to get satisfactory operation. It is, therefore, obvious that for some applications, the motor 103 may be required to operate whenever the spot 1 on the web and the cutter 29 are not synchronized and the motor 107 operating the mechanical localizer equipment is also required to operate at the same time. However, when such combined operation is not necessary, switches 204 and 205 may be selectively operated so that either motor 103 or motor 107 or both may be caused to operate when the spot on the web is not in synchronism with the knife of the cutter.

A better understanding of the invention may be had from a study of the sequence of operation involving a typical synchronizing operation for the spot on the web and the cutter. In the specific embodiment herein disclosed, reference characters 51, 52 and 53 designate the bus bars of a 60-cycle, three-phase, 440-volt source of alternating current and reference characters 41 and 44 represent the buses of a single-phase, 60-cycle, 110-volt circuit. It is to be understood, however, that the specific frequencies mentioned or voltages of the sources of supply are not part of this invention and merely disclose one application of this invention.

Assuming manually operated controller segments 43, 45, 46 and 47 are moved to bridge the contact fingers shown in connection with the controller segments, a plurality of circuits are thereby established. The transformer 36 is energized from conductors 41 and 42 and transformer 38 and the light 27 are also energized from the conductors 41 and 42. The transformer 38 has a double-wave rectifier 25 connected in the secondary windings 40 thereof and conductors 73 and 74 are connected to the direct-current junctions of the rectifier 25. To provide for the requisite sensitivity of photo-cell 17, the condensers 15 and 17 and the reactor 76, resistor sections 18 and 112 and resistor 111 are interconnected with the photo-cell 17 by conductors 79 and 80. The photo-cell 17 is so positioned with reference to the source of light 27 that the light coming from source 27 passes through the slot 228 and through the material onto the sensitive elements of the photo-cell. The resistance value of the resistor 111 as well as the potentiometer circuit involving resistors 112 and 78 increase the sensitivity of the photo-cell 17 so that a slight variation in the amount of light transmitted through the web will materially increase the current flowing in

the photo-cell circuit. Any change in the amount of current flowing in the photo-cell 17 will, by the conductor 80, increase the negative bias on the grid of the amplifier tube 19 and thus materially decrease the current flowing through tube 19.

The transformer 36 is provided with a plurality of secondaries 26, 21, 20 and 37; the secondary 26 energizes the filament of amplifier tube 18 through conductors 70 and 71; the secondary 21 10 energizes the filament of the amplifier tube 19 through conductors 68 and 69; the secondary 20 energizes the filament of the hot cathode tube 23 through conductors 63, 65, 66 and 67 and also energizes the filament of the hot cathode tube 22 15 through conductors 63, 65, 153 and 154; and the secondary 37 energizes the filament of the amplifier tube 24 through conductors 61, 62 and 56. It should be noted that the secondary 20 of the transformer 36 is provided with a tap at its mid-point and a conductor 64 leading to the resistor 13. When there is a predetermined change in the current flowing through resistors 9 and 10, either hot cathode tube 22 or hot cathode tube 23 will be caused to break down in a manner 25 more specifically pointed out hereinafter.

A double-wave rectifier 48 is interconnected with the buses 51, 52 and 53 by the controller segments 45, 46 and 47 thereby supplying the conductors 49 and 50 with a direct current potential. Assuming conductors 49 and 50 are energized, a circuit is established from conductor 50 through resistor 15, resistor 13 in parallel circuit relation to the resistor 60 and conductor 51 to the energized conductor 49. Since the energization of the 35 filament of tube 24 and the resistor sections 13 and 15 occurs at substantially the same instant, it is desirable that no operation of the hot cathode tubes can take place before the filaments have been properly heated. To prevent premature 40 operation of any of the control equipment, the condenser 59 and the resistor 58 are interconnected with the resistor sections 15, 13 and 60 and the grid of the tube 24 in such a manner that a negative bias is placed on the tube 24 for a substantially predetermined interval of time and no current can, therefore, flow from the conductor 55 to the conductor 56 prior to the expiration of such predetermined interval of time.

After the lapse of the predetermined interval 50 of time mentioned, the effect of the resistor 58 and the condenser 59 becomes negligible and an operating circuit for the relay 4 is established from the energized conductor 50 through the actuating coil of the relay 4 through conductor 55, the plate and filament of the amplifier tube 24, conductor 56, resistors 13 and 60 connected in parallel circuit relation and conductor 57 to the energized conductor 49.

For the complete operation of this system, it 60 must, of course, be assumed that the switch 127 has been closed to energize the actuating coil 128 of the line contactor 129 thereby energizing the motor 126 from the conductors 201, 202 and 203. Operation of the motor 126 drives the cutter 29 and the contact members 30, 31 and 32 through the reduction gear 131 and this motor also drives the web feeding roll 28 through shaft 123, bevel gears 124 and 125 of the mechanical localizer 225, the speed-changing device 226 and 70 the shaft 133 to the feeding roll 28 by means of the reduction gearing shown. The material 132 is fed from a supply reel 134 and passes over the idling and tension adjusting rollers 135 and 136 of the feeding roll 28 with which it is made to en-75

gage by the spring actuated idler roll 137. As will be observed, any movement of the cam 108 will operate the spring biased levers 117 and 118 pivoted at 115 and 116 in such a direction that the cone-shaped two-part pulleys 113 and 114 will change the speed of the roll 28 relative to the speed of the cutter 29. As long as the housing 122 remains fixed, the relative position of the feed roll 28 and the cutter 29 remains fixed and for any given position of the cam 108, the relative speeds of the cutter and feeding device remains constant. It is obvious that the paper or other web material after having been threaded through the machine may not be in proper position, that is, the line on which the paper is to be cut may not be at the desired position. To effect the proper positioning of the knife of the cutter with reference to the web, switch 205 is closed and controller C is operated in one or the other direction to bridge the contact fingers shown therewith, depending on the direction in which it is desired to move the cutter with reference to the web. After the cutter has been properly positioned, the controller C is again positioned as shown and switches 205 and 204 are closed, if both a speed changing adjustment and a localizer adjustment is desired during the normal operation of the paper cutter. If but one of the adjustments is desired, either switch 205 or switch 204 is closed depending upon which adjustment is desired. More often, both switches 204 and 205 are closed because, due to the hygroscopic characteristics of paper, the slippage may change from time to time and the rate of change may vary so that not only a change in the speed relation between the cutter 29 and the web feeding roll 28 is necessary but also a repositioning of the cutter 29 with reference to the web and, in consequence, roll 28 is necessary.

The web is provided with indicia on the edge thereof consisting of a black or opaque mark I about a quarter of an inch in width and one-half of an inch in depth, just sufficient to periodically cut off a large percentage of the light falling on the photo-cell 17 from the source of light 27. The specific dimensions of the printed mark are not material to this invention. It is sufficient that some indicia be placed on the web at the points it is desired the web is to be cut or at some predetermined position with reference to the desired cut so that the amount of light transmitted from the source of light to the photo-cell is periodically modified.

If the apparatus is in normal operation and the adjustment of the web with reference to the cutter as well as the speed of the cutter with reference to the web feeding device 28 has been properly adjusted and that, due to slippage or the change in dimensions of the web due to its hygroscopic character or due to the changes in temperature surrounding the web, the indicia I are not in the desired position with reference to the cutter, the contact segments 31 or 32 will be in such a position that motors 103 and 107 may be caused to operate.

Each time the printed mark I passes between the source of light 27 and the photo-cell 17, the amount of current passing through the photo-cell is materially decreased and the grid voltage of the amplifier tube 19 is changed so that the current flowing from the plate of the tube 19 to the cathode is increased, the current passing from the energized conductor 50 through conductor 81, the plate and filament of the tube 19, conductor 82, contact ring 30 (see Fig. 1), contact segment 31,

conductor 83 to the junction G, resistor 10 and conductor 85 to the energized conductor 49. The change in current through resistor 10 changes the bias on the grid of tube 23, because the grid of the hot cathode tube is connected to the junction G through the resistor 84.

The change of the bias on the hot cathode tube 23 causes this tube to break down and a circuit is thereby established from the energized conductor 50 through conductor 86, contact members 87 of the relay 4 (now closed), contact members 88 of the relay 3, resistor 33, contact members 89 of the relay 1, actuating coil 90 of the control relay 2, the hot cathode tube 23, conductors 66 and 67 through the secondary winding 20 of the transformer 36, conductor 64 to a portion of a resistor 13 and conductor 57 to the energized conductor 49. Operation of the control relay 2 causes the opening of the contact members 151 thereby preventing the operation of the control relay 1 even though the hot cathode tube 22 may for some cause break down. A circuit is also established from the energized conductor 42 through conductor 91, contact members 92 of relay 2, conductor 93, the actuating coil of the line contactor 35 and conductor 95 to the energized conductor 41. Operation of the line contactor 35 establishes a circuit between the buses 96 and 105 leading to a suitable source of direct current power, the circuit being through the conductors 97, 98 and 99, contact members 100 of the relay 35, conductor 101, series field windings 102 and 106 and the respective armatures of the motors 103 and 107, switches 204 and 205 and conductor 304 to the energized conductor 105. The motors 103 and 107 will, therefore, operate to change the speed relation between the web feeding roll 28 and the cutter 29 and also the relative position of the cutter with reference to the feed roll 28.

Since the plate voltage of the tube 23 is supplied from a source of direct current power, the tube will remain broken down even after the grid of the tube is again made negative due to a decrease in the plate current of the tube 19. The operation of the motors 103 and 107 will, therefore, continue until stopped by some other means.

It will be noted that the operation of the control relay 2 also closed the contact members 143 thereby establishing a circuit from the energized conductor 50 through the resistors 14, and 14' and 16 connected in parallel circuit relation, conductors 140 and 142, contact members 143 of relay 2, conductors 144, 145 and 85 to the energized conductor 49. The current flowing through the resistor 16 and the resistor sections 14' and 14 changes the potential of the grid of the amplifier tube 18 so that the current from the plate to the filament of tube 18 is materially increased. However, to prevent the immediate change in current through the tube 18, the potentiometer circuit, shown at the resistors 14' and 16, is utilized and interconnected with the condenser 6 and the resistor 5 by the conductor 72. After the lapse of a substantially predetermined interval of time, the current in the amplifier tube 18 will increase by an amount sufficient to operate the control relay 3. The circuit for the control relay 3 may be traced from the energized conductor 50, the actuating coil of the control relay 3, conductor 139, the plate and filament of the amplifier tube 18, conductor 71, resistor 14' and 16, conductors 140 and 142, contact members 143 of the relay 2, and conductors 144, 145 and 85 to the energized conductor 49. Since the control relay 3 is suffi-

ciently energized to operate, contact members 88 are moved to open circuit position thereby deenergizing the actuating coil 90 of the control relay 2. When the control relay 2 is deenergized, the circuit for the line contactor 35 is interrupted and the motors 103 and 107 are caused to stop. Since the contact members 143 are also open, the bias on the grid of the tube 18 is also removed and control relay 3 is deenergized and contact members 88 are again closed. Since the contact members 88, 151 and 89 are again in circuit closing positions whereas the contact members 87 remain in circuit closing position, the sequence of operation may be repeated if and when the indicia I have become displaced with reference to the cutter.

For the preceding discussion it was assumed the indicia were displaced in a given direction with reference to the cutter, say behind the cutter. If the opaque mark be ahead of the cutter, the sequence of operation is much like that heretofore discussed except that the contact segment 32 is now brought in cooperative relation with the brush connected to the conductor 155 just when the impulse from the photo-cell 17 is received. Such being the case, a circuit is established from the energized conductor 50 through conductor 81, the plate and filament of the amplifier tube 19, conductor 82, contact ring 30, contact segment 32, conductor 155, and resistor 9 to the energized conductor 49. The change in current in resistor 9 changes the bias on the grid of tube 22, when the circuit is completed through the contact ring 30 and the contact segment 32. To prevent excessive current through the grid of the hot cathode tube 22, resistor 156 is interconnected with the grid and the conductor 155.

The change of bias on the grid of the hot cathode tube 22 causes the operation of the control relay 1. The circuit for control relay 1 may be traced from the energized conductor 50 through conductor 86, contact members 87 and 88 of the relays 3 and 4, respectively, resistor 150, contact members 151 of the relay 2, actuating coil 152 of the control relay 1, the hot cathode tube 22, conductors 153 and 154, 63 and 65, the secondary windings 20 of the transformer 36, conductor 64, a portion of the resistor 13 and conductor 57, to the energized conductor 49. Operation of the control relay 1 closes the contact members 158 and 243 and opens the contact members 89. Opening of the contact members 89 prevents operation of the control relay 2. Closing of the contact members 158 establishes a circuit from the energized conductor 42 through conductors 91 and 157, contact members 158 of the relay 1, conductor 159, the actuating coil of the line contactor 34 and conductor 95 to the energized conductor 41. The line contactor 34 connects the motors 103 and 107 for reverse operation to the source of supply 96 and 105. The circuits for the motors may be traced from the energized conductor 96 through conductors 97 and 98, contact members 160 of the contactor 34, conductors 161 and 162, series field windings 163 and 164 and the armatures of the respective motors 107 and 103, switches 205 and 204 and conductor 304 to the energized conductor 105. Since the series field windings 163 and 164 are energized, the localizer equipment 225 as well as the speed changing device 226 are both operated to such a position that the indicia I is properly positioned with reference to the cutter 29.

Closing of the contact members 243 of the relay 1 completes the circuit through the resistors 14, 14' and 16 thereby effecting the operation of the amplifier tube 18 in a manner similar to that heretofore discussed. It is, therefore, obvious that 5 motors 103 and 107 will operate for a short interval of time making the necessary corrections and are then deenergized by the controlling action of the amplifier tube 18.

Attention is called to the fact that the localizer 10 equipment 225 has the housing of the differential rigidly connected to the worm wheel 121 which is operated by the worm 120 driven by the shaft 119 coupled to the motor 107. This sort of an arrangement provides an irreversible mechanism 15 20 and holds the housing 122 in fixed position during normal operation of the paper cutter. The condensers 11 and 12 interconnect with the resistor sections 7, 8, 9 and 10 and are for the purpose of controlling the time constants of the hot cathode 20 tubes 22 and 23, respectively.

It is, of course, understood that the control equipment as shown does not necessitate a source of light so disposed with reference to the photo-cell that the amount of light received by the 25 photo-cell is controlled by the amount of light transmitted through the material. Obviously, the photo-cell may be so positioned with reference to the feeding roll 28 or the idling and tension adjusting rollers 135 and 136 that light falling on 30 these rollers may be reflected on to the photo-cell 17. Any modification of the amount of light reflected due to indicia placed on the web will effect the same kind of a control as that herein described.

Furthermore, instead of positioning the photo-cell 17 as shown in Fig. 1, the light and photo-cell may be so positioned that a screen actuated by an idler roll moving with varying positions of the slack loop in the material will cause the 40 operation of the control equipment.

While the invention shown in the accompanying drawings and described in the foregoing specification represents one specific embodiment thereof, it is readily appreciated that the circuit arrangement and the control equipment utilized therewith may be modified to still fall within the spirit and scope of this invention. It is to be understood that this invention is only to be limited by the interpretation of the appended 50 claim, as required by the prior art.

I claim as my invention:

In a tubing machine for making tubular sections of equal length from elongated sheets of paper previously printed with marks at definite 55 places, power driven draw rolls to pull the web through said machine, a power driven rotary cutter for severing the web into equal sections, an individually adjustable, variable speed transmission to vary the set speed of said draw rolls with 60 respect to the speed of said rotary means to compensate for slippage of said draw rolls with respect to said web, a pilot motor for changing the setting of said variable speed transmission, two circuits for controlling said motor, a rotatable 65 switch alternately closing said circuits, a photo tube for controlling the amount of current flowing through said circuits and a source of light co-operating with said marks on said web for controlling said motor by said photo tube.
